UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS, LIMITED, OF WESTMINSTER, ENGLAND, A BRITISH COMPANY.

ENDLESS TRACK VEHICLE.

Application filed April 18, 1925. Serial No. 24,023.

To all whom it may concern:

Be it known that we, ARTHUR TREVOR DAWSON and GEORGE THOMAS BUCKHAM, both subjects of the King of Great Britain, 5 residing at Vickers House, Broadway, Westminster, in the county of London, England, have invented certain new and useful Improvements in or Relating to Endless Track Vehicles (an application for which was filed 10 in Great Britain on April 1st, 1924, Serial No. 8,257), of which the following is a specification.

This invention relates to endless track vehicles. In a known form of such vehicles 15 the tracks are composed of shoes which are pivoted together at their ends with the result that as each supporting wheel or roller passes from one shoe to the next, each shoe in turn is rocked or oscillated and undue wear 20 on the pivot pins and their bearings thus takes place.

According to the present invention the tracks comprise a system of pivoted links on which the supporting wheels or rollers bear 25 and to the pivot pins of which the shoes are freely pivoted in such a manner that, when the shoes are in contact with the ground, the axes of the pivot pins are more or less immediately above the middle portions of the 30 surfaces of the shoes. The pressure of a supporting wheel or roller is thus distributed between the shoes and the above-mentioned rocking of the shoes is thereby avoided. The portions of the shoes through which the 35 ends of the pivot pins pass are preferably in the form of bosses so shaped and arranged as to constitute driving projections for engagement by the sprocket wheels for driving the tracks.

40 When the track is intended for use with pairs of laterally separated supporting wheels or rollers it is composed of alternate inner single and outer double links of which the latter are situated laterally apart at a 45 distance corresponding to the lateral separation of the supporting wheels or rollers, whilst the inner links are formed with laterally projecting flanges the upper surfaces of which constitute continuations of the upper 50 surfaces of the outer links and are also formed with substantially vertical thrust plates or flanges situated between the paths

of the supporting wheels or rollers so that the said thrust plates take the lateral thrust of the said wheels or rollers during turning 55 movements of the vehicle.

In order that the said invention may be clearly understood and readily carried into effect, the same will now be described more fully with reference to the accompanying 60 drawings, in which:—

Figure 1 is a side elevation partly in section, showing a track constructed in accordance with the invention.

Figure 2 is an inner plan of Figure 1, 65

Figure 3 is a section taken approximately on the line 3, 3 of Figure 2.

The track shown is for use with pairs of laterally separated supporting wheels or rollers and is composed of alternate inner 70 single links A, A . . . and outer double links B, B . . . The outer links are situated laterally apart at a distance corresponding to the lateral separation of the supporting wheels or rollers and each of the inner links 75 has two laterally projecting flanges A¹, A¹ the inner surface of which form continuations of the inner surfaces of the outer links. The said inner links also have substantially vertical thrust plates or flanges A², A² situated 80 between the paths of the supporting wheels or rollers so that the said thrust plates take the lateral thrust of the said wheels or rollers during turning movements of the vehicle. The thrust plates of 85 each link are preferably cross-connected by webs A³, A³ for stiffening purposes so as to more effectively resist the side thrust. The pivot pins C, C . . . connecting the links together pass through bearings in the inner 90 links A, A . . . (these bearings extending the whole width of these links) and through holes in the outer links B, B . . . the outer links preferably forming a tight fit with the pivot pins. These pins project laterally 95 beyond the outer links and fit loosely in bosses D, D on the shoes D¹, D¹, which are thus free to swing into any desired position in accordance with the formation of the ground with which they are in contact. The 100 portions of the shoes that come into contact with the ground may be constituted by pressed steel plates riveted to the other portions of the shoes as shown in Figure 1, and

said portions may be formed with transverse corrugations to increase the adhesion with the ground.

It will be observed that the bosses D, D of the shoes are arranged midway between the sides of the shoes so that the axes of the pivot pins C, C . . . are immediately inwardly of the centre of the surfaces of the shoes in order to distribute the pressure of 10 the supporting wheels or rollers between the shoes. The said bosses are rounded so as to constitute driving projections for engagement by the sprocket-wheels for driving the track.

15 What we claim and desire to secure by Letters Patent of the United States is:—

1. A track for endless track vehicles comprising alternate inner single and other double links connected together by pivot pins, thrust plates formed on said inner

links, said inner and outer links forming a path adapted for use with supporting rollers.

2. A track for an endless track vehicle, for use with pairs of laterally separated supporting rollers, comprising alternate inner single and outer double links which are connected together by pivot pins and of which the outer double links are situated laterally apart at a distance corresponding to the lateral separation of the supporting rollers, laterally projecting flanges on said inner links the inner surfaces of these flanges constituting continuations of the inner surfaces of the outer links, and substantially vertical 30 thrust plates formed on said inner links and situated between the paths of the supporting rollers.

ARTHUR TREVOR DAWSON.
GEORGE THOMAS BUCKHAM.
